[57] **CLAIM**

The ornamental design for a louvered vent for boats, substantially as shown and described.

DESCRIPTION

FIG. 1 is a side elevational, perspective view of the louvered vent for boats showing my new design;
FIG. 2 is a top, plan view thereof;
FIG. 3 is a side elevational view thereof;
FIG. 4 is a bottom view thereof;
FIG. 5 is an end elevational view thereof, it being understood that both end views are the same;
FIG. 6 is a cross-sectional view taken along the plane 6—6 of FIG. 2; and
FIG. 7 is a cross-sectional view taken along the plane 7—7 of FIG. 6;
FIG. 8 is a cross-sectional view taken along the plane 8—8 of FIG. 2; and
FIG. 9 is a cross-sectional view taken along the plane 9—9 of FIG. 2.
